UNITED STATES PATENT OFFICE.

FRANK ZALESKI, OF SOMERVILLE, MASSACHUSETTS, ASSIGNOR TO THE REECE BUTTON HOLE MACHINE COMPANY, OF BOSTON, MASSACHUSETTS, A CORPORATION OF MAINE.

SEWING-MACHINE.

1,255,970.

Specification of Letters Patent. Patented Feb. 12, 1918.

Application filed November 2, 1915. Serial No. 59,312.

To all whom it may concern:

Be it known that I, FRANK ZALESKI, a subject of the Emperor of Germany, residing at Somerville, county of Middlesex,

5 State of Massachusetts, have invented an Improvement in Sewing-Machines, of which the following description, in connection with the accompanying drawing, is a specification, like characters on the drawing representing like parts.

This invention relates to sewing machines and has for its object to provide novel means for holding the needle thread at the beginning of the stitching operation so as to insure the proper formation of the first 15 stitch. My invention provides a mechanism for thus holding the end of the needle thread at the beginning of the stitching operation which operates beneath the work and clamps the needle thread on the under face of the work. The thread-clamping means is constructed so that when the machine is set in operation and the needle makes its first penetrating thrust through 20 the work thereby to carry the end of the needle thread through the work, said thread-clamping device will seize the end of the needle thread as the needle is withdrawn and hold said thread while the needle is 25 retracted and while the next succeeding stitches are being made. The operator is thus entirely relieved from the duty of holding the end of the needle thread to insure the correct formation of the first stitches.

30 My improvement has the advantage over those devices that clamp the needle thread above the work that the projecting end of needle thread which is held by the clamp will be situated on the underside of the 35 work rather than on the top of the work. The presence of a projecting end of thread on the top face of the work is often objectionable because the top face is frequently the finished face and to make a finished 40 product requires the cutting by hand of any projecting thread ends.

45 My invention is capable of being used with sewing machines of different types, and in order to illustrate it, I have chosen 50 to show it herein as it might be applied to a buttonhole sewing machine of the so-called "Reece" type, examples of which may

be found in the following United States Patents:

No. 655,637, August 7, 1900;

No. 1,030,589, June 25, 1912.

55

I wish to state, however, that the invention is not limited in its use to sewing machines of this particular type, as with suitable modifications, it can be applied to a variety of different types of sewing machines.

I will first describe the selected embodiment of the invention herein illustrated and then point out the novel features of the invention in the appended claims.

Figure 1 of the drawings is a partial transverse sectional view through a button-hole sewing machine of the so-called "Reece" type, the section being taken through the frame to show the under thread mechanism;

Fig. 2 is a partial sectional view taken at right angles to Fig. 1;

Fig. 3 is a top plan view of the base frame of the machine with the work-clamping plates removed thereby showing the under thread mechanism in plan view;

Figs. 4, 5, 6 and 7 are diagram views showing the operation of my improved thread-clamping device.

As stated above, my invention relates to a thread clamping device situated beneath the work support of a sewing machine and in position to seize and hold the end of the needle thread which is inserted through the work upon the first penetrating thrust of the needle when the stitching operation is begun, thereby holding the thread from beneath the work while the first few stitches are being formed. Where the invention is used in connection with a two-thread sewing machine, that is, a sewing machine which has both upper thread mechanism and lower thread mechanism, I may associate the thread-clamping device with the under thread mechanism, although this is not essential to the invention.

In the illustrated embodiment of the invention which is especially designed for use in connection with a "Reece" buttonhole sewing machine, the thread-clamping device for the upper or needle thread is associated with the under thread mechanism.

In buttonhole sewing machines of this type, the under thread mechanism is mounted upon a rotatable turret or support which is rotated as the stitching is carried around 5 the ends of the buttonhole, and in the illustrated embodiment of my invention the thread clamp is mounted on this rotatable turret, means being provided to actuate the thread clamp to seize the end of the needle 10 thread which is carried through the work by the first penetrating thrust of the needle.

Before describing the thread-clamping device in detail I will refer briefly to the principal elements of the sewing machine herein 15 illustrated and to which the invention is applied.

1 indicates a portion of the main frame of the sewing machine which is provided with the usual overhanging arm 2 in which reciprocates 20 a noneedle bar 3 carrying the needle 4 of the upper thread-handling mechanism. The lower or under thread-handling mechanism is mounted on a rotatable turret or stock 5, as usual in buttonhole sewing machines 25 of this class, said stock being mounted for rotation in bearings 6 and 7 carried by a depending portion 8 of the main frame 1. This under thread-handling mechanism comprises the usual under needle 9 which is oscillated back and forth through a throat-plate 10 carried by the turret or rotatable stock 5, and a looper 11 which also has an oscillatory movement and which operates to enter and open the loop of upper needle 30 thread, which has been inserted through the fabric by the penetrating thrust of the upper needle 4, and to hold said loop open while the lower needle 9 passes therethrough. The needle 9 is shown as sustained in a 35 needle carrier 12 which is pivotally mounted at 13 upon the turret, said needle carrier having an arm 14 rigid therewith which is connected by a link 15 to an actuating rod or shaft 16 that reciprocates 40 through bearings formed in the rotatable turret or stock 5 and is situated axially thereof. The looper 11 is sustained by a looper carrier 17 which is also actuated from the shaft or bar 16, all as usual in sewing 45 machines of this character and as set forth in the above-mentioned patents.

It will be understood, of course, that in the operation of the machine, the under needle is advanced upwardly through the 55 fabric, thus carrying a loop of under thread to the upper side of the fabric, and the upper needle then descends through the loop of under thread and the under needle is retracted, and that the looper 11 then enters 60 the loop of upper thread as the upper needle 4 is retracted and carries said loop into position to be entered by the under needle 9 upon its next forward movement, this operation being repeated so that the upper and under 65 threads are concatenated in the usual man-

ner provided for by two-thread sewing machines of this character. During the stitching of the buttonhole, the upper and under thread-handling mechanisms are rotated so as to carry the stitching around the ends of the buttonhole, and in the construction herein illustrated, this rotative movement is provided for by means of pinions 18 and 19 secured to the needle bar and turret 5, respectively, said pinions meshing with segmental gears 20 and 21 that are carried by a vertically-extending shaft 22. Suitable mechanism, not shown, is provided for turning the shaft 22, thereby to turn the upper and under thread-handling mechanisms as required 75 to effect the stitching around the ends of a buttonhole.

220 designates work-holding plates on which the work is supported and 23 are the usual work clamps by which the work is clamped to the work-holding plates 220. 24 is the buttonhole-cutting element which is shown as pivotally mounted to the main frame at 25. This element is provided with a cutting knife 270 which cooperates with an anvil 26 to cut the buttonhole, and in the construction shown, the anvil is sustained upon a supporting member 27 which is pivotally mounted at 28 to the frame so that it can move from the dotted to the full line position Fig. 2. The dotted line position shows the inoperative position of the anvil and the full line position shows the operative position which it occupies while the buttonhole is being cut. The anvil 95 is moved from its inoperative to its operative position by means of a cam finger 280 carried by a shaft 29, said shaft being oscillated in timed relation with the operation of the sewing machine to cause the anvil to be thrown into its operative position shown in full lines Fig. 2 at the time that the buttonhole is to be cut.

In the operation of sewing machines of this type it is customary to cut the buttonhole before the stitching operation.

In operating the machine the operator places the work beneath the work clamp 23 and then sets the machine in operation. The work clamps are closed onto the work and the anvil is moved into its operative position and the cutter 24 is operated to cut the buttonhole. The work-holding plates 220 and work clamps 23 with the work clamped between them, and the stitch-forming mechanism are moved relative to each other to bring the slit of the buttonhole in position to have the over-edge stitches formed thereon by the stitch-forming mechanism, and the stitch-forming mechanism is then started, 125 thereby to form the over-edge stitches, during which time the upper and under thread-handling mechanisms are turned to effect the stitching around the buttonhole.

The above is a brief reference to the con- 130

struction and operation of some of the important elements of a buttonhole sewing machine.

As stated above, my invention relates to a thread-clamping and holding device constructed to take the end of the upper needle thread *t* which is inserted through the work upon the first penetrating thrust of the needle and to hold this end while the first stitches are being formed. In the present embodiment of my invention this thread holder and clamp comprises relatively-fixed and movable thread-clamping members carried by the rotatable turret or stock 5, and means for opening or separating said members when the machine is set in operation, and then for releasing said members so that they close together just after the upper needle 4 has made its first penetrating thrust so that the end of the needle thread *t* carried through the work by such penetrating thrust will be gripped between the thread-holding members and held while the stitching operation continues. Any suitable means may be employed for opening or separating the thread-clamping members and then for clamping them together again which is properly actuated from some moving part of the machine in timed relation with the operation of the needle 4.

In the illustrated embodiment of my invention the movable thread-clamping member is shown at 30 and it is situated directly beneath the throat-plate 10. The fixed clamping member may be any fixed element with which the movable member 30 can cooperate. In the construction shown I provide the stem 32 of the throat-plate with a fixed clamping face 31 with which the element 30 cooperates to clamp the upper thread *t*.

In order to provide for moving the relatively-movable clamping member 30 toward and from the fixed clamping face 31, I propose to mount the member 30 on an arm 33 which is herein shown as pivoted at 34 to a plate 35 secured to the stock or turret 5. This arm 33 is acted upon by a suitable spring 36 which tends to swing said arm into a position to hold the relatively-movable thread-clamping member in its thread-clamping or operative position.

The thread-clamping member 30 is so constructed and arranged that when it is in its operative position against the fixed clamping face 31, it occupies a position at one side of the path of movement of the upper needle 4, as shown in Figs. 4 and 7, while when it is in its open position, it occupies a position at the opposite side of the path of the needle 4, as shown in Fig. 5.

The operation of the thread-clamping member 30 is illustrated diagrammatically in Figs. 4 to 7. Before the machine is set in operation the thread-clamping member 30 is

in its operative position, shown in Fig. 4, and the needle 4 is raised. When the machine is set in operation, the thread-clamping member is moved into its open position shown in Fig. 5 before the needle 4 makes its first penetrating thrust so that when the needle makes its first descent it passes down between the two clamping members 30 and 31, as shown in Fig. 5. This movement of the needle carries the end *t'* of the needle thread through the work *w* and between the two clamping members. At this time the looper 11 is moved into the loop of needle thread, as shown in Fig. 6, and the needle 4 is then retracted. As the needle is retracted, the engagement of the loop of needle thread with the looper draws the end *t'* of thread through the work, and as soon as the needle has been retracted, the movable thread-clamping member 30 is moved into its operative position thereby clamping the end *t'* of needle thread between itself and the fixed clamping member 31, as shown in Fig. 7. The thread is held in this position while the succeeding stitches are being formed, thus insuring the proper formation of the first stitch. The end *t'* of the needle thread is located on the under side of the work *w*, and this is a very great advantage in many instances because the upper side of the work is usually the finished side and any projecting end of thread extending from the upper side makes an imperfection in the work which can only be remedied by cutting the end of the thread by hand.

The movable clamping member 30 may be actuated from any suitable moving part of the machine the operation of which is properly timed relative to that of the upper needle 4 so as to open or separate the thread-clamping members before the needle 4 makes its first penetrating thrust. In the illustrated embodiment of my invention I have chosen to use the movement of the anvil carrier 27 from its inoperative to its operative position for effecting the opening movement of the thread-clamping members, but this might be accomplished from some other moving part of the machine without departing from the invention. I have chosen herein to actuate the thread-clamping members from the anvil carrier 27 because in the operation of the machine the anvil carrier moves forwardly into its operative position before the stitching operation begins and by actuating the thread-clamping member 30 from the anvil carrier 27, the opening of the thread clamp is insured before the needle makes its descent, but as stated above, the thread clamp 30 might be actuated from some other part which has a properly-timed movement relative to that of the needle 4. In the construction herein shown I provide a lever 37 which is pivotally mounted upon a post 38 secured to

the portion 8 of the machine frame, one end 39 of said lever being situated in front of the anvil carrier 27, as shown in Fig. 3. The opposite end of said lever is loosely connected to a sliding actuator 40 which is mounted to slide on guiding struts or pins 41 carried by the flange portion 42 of the frame 1. This actuator 40 is formed with slots 43 in which the studs 41 operate. The 10 end of the actuator is bent laterally, as shown at 45, and is provided at its end with an adjustable screw 46 having a head 47 that is adapted to engage a pin or projection 48 extending from the pivoted 15 arm 33.

The means for rotating the turret is such that when the machine is started in operation and the anvil 27 swings forward, the turret will have approximately the position 20 shown in the drawings and the projection 48 will be in line with the head 47 of the adjusting screw 46. When the machine is started in operation and the anvil carrier 27 is moved forwardly into its full line position, it engages the end 39 of the lever 37 and swings said lever into the position shown in Fig. 3, thereby moving the actuator 40 rearwardly or to the right, Fig. 3. This movement brings the head 47 of 30 the screw 46 against the projection 48 and swings the arm 33 about its pivot 34 thereby opening the thread clamp and carrying the movable member 30 into the position shown in Figs. 2, 3 and 5. Inasmuch as the 35 upper needle 4 does not descend immediately that the anvil carrier 27 is moved forwardly, I have provided means herein for locking the thread-clamping member 30 in its open position until the stitching operation is begun. For this purpose I have provided the 40 arm 33 with an extension 49 and have provided a swinging locking plate 50 which is pivotally mounted at 51 on the plate 35. Said plate 50 is provided with a pin or projection 52 that normally is situated at one 45 side of the extension 49 and rests against the edge thereof, as shown in Fig. 1. The plate 50 is also provided with an arm 53 which is actuated upon by a suitable spring 54 that tends to swing said plate to the left, 50 Fig. 1. When the arm 33 is moved by the actuator 40 into the position shown in Fig. 2, the extension 49 of the arm 33 is withdrawn from the projection 52 and the spring 54 then moves the plate 50 to the left, 55 Fig. 1, thereby carrying the pin 52 behind the extension 49 and locking the thread-clamping members open. The thread-clamping members will remain open while the 60 anvil 26 is retracted and while the work-holding mechanism is moved to bring the buttonhole into stitching position.

Means are provided for releasing the thread-clamping members during the formation of the first stitch and in proper timed

relation to the operation of the stitching mechanism to cause the thread clamp to seize and hold the end *t'* of the needle thread, as above described. This is herein provided for by a releasing member 55 70 which is secured to the actuating shaft or rod 16 and which engages a cam projection 56 formed on the plate 50 during the first movements of the bar 16 thereby to shift the position of the plate 50 sufficiently to carry 75 the pin 52 out from under the arm 49. The member 55 is pivotally mounted on a stud 57 carried by the bar 16 and is provided with a nose 58 situated to engage the cam projection 56 of the member 50 when the latter is 80 in the dotted line position. This member 55 is also acted upon by a spring 59 which yieldingly holds it against a stop 60. When the stitching operation is commenced the bar 16 first rises to carry the lower needle 9 85 up through the buttonhole slit and during this movement the nose 58 wipes by the cam projection 56 without moving the part 50, the spring 59 permitting this operation. When the bar 16 descends, however, to withdraw the under needle 9, the nose 58 will engage the cam projection 56 and because the movement in one direction of the releasing member 55 is limited by the stop 60, the engagement of the nose 58 with the cam projection 56 will force the member 50 backwardly into the full line position, Fig. 1, 90 thereby carrying the pin 52 out from under the extension 49 and allowing the spring 36 to move the thread clamp 30 into its operative position. This releasing of the thread clamp occurs just while the needle 4 is being retracted after its first penetrating thrust and in time so that the clamping members 30, 31 will engage and 105 clamp the end *t'* of needle thread. The end of the needle thread is thus securely held so that the first stitch will be properly formed, and moreover, when the buttonhole is finished the projecting end of the needle thread 110 is on the underside of the work where it will not be seen in the finished product.

While I have described in some detail a particular embodiment of my invention, yet I wish to make it clear that the invention is 115 not limited to the constructional details shown and that the particular shape of the thread-clamping device and the particular means for operating it will vary with the type of sewing machine with which the invention is used.

I claim:

1. In a buttonhole sewing machine, the combination with work-holding means, of buttonhole-cutting mechanism, stitch-forming mechanism including a needle operating from above the work-holding means, and means rendered operative by the buttonhole-cutting mechanism to seize and hold the end of the needle thread which is inserted 130

through the work at the first penetrating thrust of the needle.

2. In a sewing machine, the combination with work-holding means, of upper thread-handling mechanism, a turret situated below said work-holding means, under thread-handling mechanism carried by said turret, a thread-clamping element movably carried by said turret, and means to actuate said element upon the commencement of the stitching operation to cause it to clamp against a fixed part of the turret the end of the needle thread which is inserted through the work by the first penetrating thrust of the needle.

- 15 3. In a sewing machine, the combination with work-holding means, of stitch-forming mechanism including a needle above the work-holding means, an under-thread-handling mechanism beneath said work-holding means, a thread-clamping device beneath the work-holding means and comprising two clamping members which are held separated as the needle makes its first penetrating thrust, and means controlled by the under-thread-handling mechanism to close said clamping members onto the end of the upper thread which is inserted through the work by said first penetrating thrust of the needle.

4. In a sewing machine, the combination with work-holding means, of stitch-forming mechanism including a needle above the work-holding means and under complementary thread-handling mechanism mounted for bodily turning movement, a pair of thread-clamping elements, one of which is fixed relative to the axis of said turning movement and the other of which is movable toward and from the fixed element and both of which partake of the turning movement of the under thread-handling mechanism, and means to actuate said elements upon commencement of the stitching operation to cause them to clamp the end of the needle thread which is inserted through the work upon the first penetrating thrust of the needle.

5. In a sewing machine, the combination with work-holding means, of stitch-forming mechanism including a needle, means for actuating the stitch-forming mechanism, relatively-fixed and movable thread-clamping elements situated below the work-holding means, means rendered operative when the sewing machine is set in operation to separate said clamping elements, a locking device to hold them separated, and means actuated by the operation of the stitch-forming mechanism during the formation of the first stitch to release said locking device whereby the clamping elements are closed together and operate to clamp the needle thread beneath the work.

6. In a sewing machine, the combination with work-holding means, of stitch-forming mechanism including a needle above the

work, a spring-actuated thread-clamping device beneath the work-holding means, means rendered operative when the machine is set in operation to open said thread-clamping device, a locking device to hold said thread-clamping device open, and means actuated by the operation of the stitch-forming mechanism during the formation of the first stitch to release said lock thereby allowing the clamp to close upon and clamp the end of the needle thread which has been inserted through the work.

7. In a sewing machine, the combination with work-holding means, of stitch-forming mechanism including a needle above the work, a spring-actuated thread-clamping device beneath the work-holding means, means rendered operative when the machine is set in operation to open said thread-clamping device, locking means to hold said thread-clamping device open, and means actuated by the operation of the stitch-forming mechanism during the formation of the first stitch to release said locking means as the needle is withdrawn, thereby to allow the clamp to close upon and clamp the end of the needle thread which has been inserted through the work.

8. In a buttonhole sewing machine, the combination with buttonhole-cutting mechanism, of stitch-forming mechanism including a needle operating above the work, a thread-clamping device beneath the work, means actuated by the cutting mechanism to open the clamping device, and means to close said device onto the end of the needle thread which is inserted through the work by the first penetrating thrust of the needle.

9. In a buttonhole sewing machine, the combination with work-holding means, of buttonhole-cutting mechanism, stitch-forming mechanism including a needle operating from above the work-holding means, and means beneath the work-holding means and rendered operative by the buttonhole-cutting mechanism to seize and hold the end of the needle thread which is inserted through the work at the first penetrating thrust of the needle.

10. In a buttonhole sewing machine, the combination with work-holding means, of buttonhole-cutting means, stitch-forming mechanism including a needle operating from above the work, thread-clamping means beneath the work-holding means and comprising relatively - movable clamping members, means actuated by the buttonhole-cutting mechanism to open the clamping members prior to the beginning of the stitching operation, and means to close said clamping members on to the end of the needle thread which is inserted through the work at the first penetrating thrust of the needle.

11. In a buttonhole sewing machine, the

combination with work-holding means, of buttonhole-cutting mechanism, stitch-forming mechanism including a needle operating from above the work, thread-clamping means beneath the work-holding means and comprising relatively movable clamping members, means actuated by the buttonhole-cutting mechanism to open the clamping members prior to the beginning of the stitching operation, and means actuated by the stitch-forming mechanism to close said clamping members onto the end of the needle thread which is inserted through the work at the first penetrating thrust of the needle.

12. In a buttonhole sewing machine, the combination with work-holding means, of buttonhole-cutting mechanism, stitch-forming mechanism including a needle operating

from above the work-holding means and under complemental thread-handling mechanism mounted for bodily turning movement, thread-clamping means mounted for turning movement with the under thread-handling mechanism and comprising relatively movable clamping members, means actuated by the cutting mechanism to open the clamping members prior to the beginning of the stitching operation, means actuated by the stitch-forming mechanism during the formation of the first stitch to close said clamping members onto the needle thread which is inserted through the work at the first penetrating thrust of the needle.

In testimony whereof, I have signed my name to this specification.

FRANK ZALESKI.
